Harry Gillett

By J. B. Hull.

ATTORNEY

UNITED STATES PATENT OFFICE.

HARRY GILLETT, OF CLEVELAND, OHIO.

COMPOSITE ROOFING.

1,044,773.

Specification of Letters Patent.

Patented Nov. 19, 1912.

Application filed August 1, 1910. Serial No. 574,769.

To all whom it may concern:

Be it known that I, HARRY GILLETT, a citizen of the United States, residing at Cleveland, in the county of Cuyahoga and State of Ohio, have invented a certain new and useful Improvement in Composite Roofing, of which the following is a full, clear, and exact description, reference being had to the accompanying drawings.

10 This invention relates to composite roofings; that is to say, to roofings which are built up into a continuous structure as they are laid, as distinguished from roofings which are made up in advance and are afterward laid and which, when so laid, present distinct joints between the adjacent sections.

15 The purpose of this invention is to provide, in combination with a masonry foundation, (such as concrete, tile, etc.) a light, strong, water-proof, fire-proof and durable composite roofing which is adaptable to the varying conditions and incidents of use, which shall be extremely convenient of application, and which will dispense with the 20 use of a slag or gravel coating.

25 A further object of the invention is to provide a practical composite roofing for masonry foundations, which roofing consists largely of inorganic, solid-fibered material 30 which, while being substantially fire-proof as well as non-heat-conductive, will effectually retain, with a minimum of evaporation, the water-proofing material applied thereto.

35 With the foregoing objects in view, the invention may be defined as consisting further of the novel features of construction and the combinations of parts and elements to be hereinafter particularly described and 40 pointed out in the claims.

In the accompanying drawings, Figure 1 45 is a fragmentary plan view of a piece of roofing constructed in accordance with my invention, the roofing being designed with special reference to a roof structure having a masonry surface or roofing foundation, parts of the overlying layers being turned back to disclose the underlying layers and to illustrate the manner of building up the roofing.

50 Fig. 2 represents a perspective view of a portion of a roof, illustrating the manner in which the gutter or waterway is reinforced; Fig. 3 represents an enlarged sectional detail corresponding to the line 3—3 of Fig. 1;

55 Fig. 4 represents a similar view taken along the gutter or waterway shown in Fig. 2, and

Fig. 5 a greatly enlarged sectional detail of the roofing shown in Fig. 1.

Describing the parts by reference characters, 1 denotes the masonry foundation to which the roofing is applied. This foundation is prepared for the reception of the composite roofing by first applying to its surface a coating 2 of suitable liquid filler, such as asphaltum. After drying or solidifying sufficiently, a coating 3 of adhesive material, preferably asphalt, is applied to the surface in courses. The preliminary treatment of the foundation in the manner described insures efficient adhesion between the coating 3 and the foundation.

In the case of a roof of ordinary pitch or slope, the first coat will be applied to the lower end of the foundation and a sheet or course 4 of water-proofed fibrous inorganic material, preferably asbestos felt which has been saturated with asphalt, will be rolled down into adhesive engagement with the coating 3. It is susceptible of demonstration that the coefficient of expansion of asphaltum-saturated asbestos felt is substantially the same as that of masonry, such as reinforced concrete or tile, and, whenever herein "fibrous inorganic material" is referred to, thereby is meant a material having the same approximate coefficient of expansion as such asbestos felt. A second course of the same or similar adhesive material will then be applied to the first sheet or course 4 and to a course of the coated foundation thereabove, as indicated at 3^a. A course or strip 4^a of the same kind of material as the strip 4 will then be rolled down into adhesive engagement with the strip 4 and with the portion of the roof 50 thereabove to which the adhesive coating 3^a has been applied. A coating 3^b of adhesive material of the same character as the coatings 3 and 3^a is then applied to the upper surface of the strip 4^a and to a strip or course of the preliminary coated foundation thereabove. A strip or course 4^b of the same kind of material as the strips 4 and 4^a is then rolled down into adhesive engagement with the strip 4^a and the portion of the roof to which the coating 3^b has been applied. A coating 3^c similar to the coatings 3, 3^a and 3^b is then applied to the upper portion of the surface of the strip 4^b and to a portion of the roof thereabove 100 of substantially the same width as the portions or courses to which the coatings 3^a and

105 110

3^b have been applied, and a full width strip 4^c of the same kind of material as the preceding strips is rolled down into adhesive engagement with the strip 4^b and the portion of the roof foundation thereabove to which the coating 3^c has been applied.

The strips 4^b and 4^c are of the full or maximum width which will be employed and the lower portion of the coating 3^c and the lower edge of the strip 4^c will overlap the upper edge of the strip 4^b. In similar manner, additional strips 4^d, etc., will be applied to each subsequent strip or layer and to a portion of the roof foundation thereabove, in each case overlapping the lower end of each course with the upper end of the third course therebeneath. When the roof has been laid in this manner, the foundation will be covered by three plies 20 or thickness of water-proofed, inorganic, solid-fibered material, the lower edge of each outer course or strip overlapping the upper edge of each third or bottom strip beneath, as clearly indicated in Fig. 3. A 25 final coating 5 of asphaltum or paint will be applied to the outermost plies or strips 4^b, 4^c, etc., to give a finished appearance to the roof. On steep surfaces, the manner of applying the roofing courses will be the 30 same as described except that such courses will be laid up and down the roof instead of across.

In Figs. 2 and 4 there is illustrated the manner in which the composite roofing is applied to the gutter or waterway at the 35 lower end of a roof. The masonry foundation 1 is deflected laterally at its lower end, as shown at 6, and such laterally deflected end abuts against the vertical wall 7, which is preferably of masonry and which is shown as provided below the top and in its inner face with a nailing strip 8, preferably of wood; or any other securing means may be applied to said wall.

The preliminary coating 2 will be applied 45 to the gutter 6 as well as to the inner face of the wall 7. One or more plies of water-proofed fibrous material, similar in character to the plies 4, 4^a, etc., will be laid longitudinally of the gutter. The lowermost ply 50 will be rolled into adhesive engagement with the gutter, with the wall 7, and the foundation 1, by means of the coating 4^c of adhesive material (preferably asphalt). One side of the ply 9 will project upwardly 55 along the roof foundation 1 a considerable distance—a foot or more—and the other side will project upwardly along the inner face of the wall 7 a material distance. One or 60 more additional plies 10 may be used, similar in construction and arrangement to the ply 9 and rolled into engagement therewith through an intervening coating 11 of asphalt or similar adhesive. The uppermost ply 10 65 will be coated with asphalt (or similar ad-

hesive) along with the various strips or courses of the roof foundation, and the strips or plies 4, 4^a, 4^b, 4^c, etc., will be secured to the foundation 1, to each other, and to the uppermost gutter reinforcing ply 70 by means of suitable courses of asphalt or similar adhesive. It will be observed that owing to the steepness of the roof, the various plies or strips 4, 4^a, 4^b, 4^c, etc., are laid up and down the roof instead of transversely, and that their upturned overlapping ends may be secured to the wall 7 in any convenient manner, as by nailing to the strip 8, as indicated at 12. As in the case of the roofing shown in Figs. 1 and 3, 80 a final coating 5 of asphaltum or paint will be applied to the outermost plies or strips to give a finished appearance to the roof.

By the construction herein described, I am enabled to provide a composite roofing 85 having a masonry foundation which roofing is light, durable, water-proof, and which on account of its lightness, will not require frequent fastening to prevent slipping or sagging, as is necessary with roofing of heavier 90 material. The roofing consists mainly of water-proofed, inorganic, solid-fibered, material in which the capillarity is reduced to a minimum (thus minimizing evaporation) and which material, and the roofing formed 95 therefrom, is fire-proof, leak-proof and practically non-heat-conductive, while the roof is light in weight but capable of withstanding all ordinary incidents of use.

Because of the coefficient of expansion of the fibrous inorganic material being substantially the same as that of the masonry foundation, the expansion and contraction of the latter does not loosen the roofing from the foundation, as is apt to be the case with 105 organic fibrous material.

Having thus described my invention, what I claim is:

1. A composite roof comprising a masonry foundation having applied thereto the following coatings: first, a coating of liquid air-drying filling material; second, a coating of molten adhesive material; third, a coating of overlapping strips or plies of water-proofed fibrous inorganic material, having 110 approximately the same coefficient of expansion as the foundation, said plies or strips being rolled into adhesive engagement with the foundation through the second coating and into adhesive engagement with each other through a similar coating interposed 115 between the overlapping portions of the plies or strips.

2. In a roof, the combination of a masonry foundation having a gutter, said foundation and gutter having a coating of liquid, air-drying filling material applied thereto and a coating of molten adhesive material applied thereto over the preliminary coating, one or more plies of fibrous inorganic 125

water-proofed material applied to the gutter, each ply having an edge extending along the foundation above said gutter, said ply or plies being secured in place by the coating of adhesive material, a covering for the foundation and gutter reinforcing ply or plies consisting of a series of overlapping strips or plies of water-proofed fibrous inorganic material rolled down into engagement with each other and with the foundation and with the upper surface of the gutter reinforcement by means of an adhesive coating, and a final liquid coating applied to the last covering.

15 3. In a roof, the combination of a concrete foundation having a gutter, with an upwardly projecting wall beyond the outer edge of said gutter, said foundation, gutter and wall having applied thereto a coating of filling material, one or more strips of water-proofed fibrous inorganic material applied to the gutter and extending longitudinally thereof, the lowermost strip being secured to the gutter, to the lower portion of the wall and the lower portion of the foundation by means of adhesive material applied in a fluid condition, and a covering consisting of a series of overlapping strips or plies of inorganic fibrous material having water-proofing applied thereto and rolled into adhesive engagement with each other, with the foundation, the upper gutter-reinforcing strip and the wall by means of a similar adhesive and secured at their upper edges to said wall.

4. In a construction of the character set forth, the combination of a masonry foundation having a gutter and an upwardly projecting masonry wall beyond the outer edge of the gutter, said wall having on its inner

face a nailing strip, said foundation, gutter and wall having applied thereto a coating of liquid, air-drying filling material, one or more strips of water-proofed fibrous inorganic material applied to the gutter and extending longitudinally thereof, the lowermost strip being secured to the gutter, to the lower portion of the wall and to the lower portion of the foundation by means of molten adhesive material, a covering consisting of a series of overlapping strips or plies of inorganic fibrous material having water-proofing material applied thereto and rolled into adhesive engagement with each other, with the foundation, the upper gutter-reinforcing strip and the wall by means of a similar adhesive and extending as high as the nailing strip, a strip covering the upwardly projecting ends of the overlapping strips, and nails securing the last mentioned strips to the nailing strip.

5. A composite roof comprising a masonry foundation having applied thereto the following coatings: first, a coating of filling material; second, a coating of molten adhesive material; third, a coating of overlapping strips or plies of water-proof asbestos felt, said plies or strips being rolled into adhesive engagement with the foundation through the second coating and into adhesive engagement with each other through a similar coating interposed between the overlapping portions of the plies or strips.

In testimony whereof, I hereunto affix my signature in the presence of two witnesses.

HARRY GILLETT.
